(57) **CLAIM**

The ornamental design for a distance measurement device with flip-up protector screen, substantially as shown and described.

DESCRIPTION

FIG. 1 is a front perspective view of a distance measurement device with flip-up protector screen with the flip-up protector screen in an open position;

FIG. 2 is a top plan view of the distance measurement device with flip-up protector screen of FIG. 1;

FIG. 3 is a right side elevation view of the distance measurement device with flip-up protector screen of FIG. 1, the left side elevation view being a mirror image thereof;

FIG. 4 is a front elevation view of the distance measurement device with flip-up protector screen of FIG. 1;

FIG. 5 is a rear elevation view of the distance measurement device with flip-up protector screen of FIG. 1;

FIG. 6 is a bottom plan view of the distance measurement device with flip-up protector screen of FIG. 1; and,

FIG. 7 is a front perspective view of the distance measurement device with flip-up protector screen of FIG. 1 with the flip-up protector screen in a closed position.

The dashed lines of the push-buttons indicate that the push-buttons form no part of the claimed design.
